(57) **CLAIM**

The ornamental design for a remote control apparatus for industrial endoscope, as shown and described.

DESCRIPTION

FIG. 1 is a front, top and right side perspective view of a remote control apparatus for industrial endoscope showing our new design;

FIG. 2 is a rear, bottom and left side perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a right side elevational view thereof;

FIG. 8 is a left side elevational view thereof;

FIG. 9 is an enlarged front, top and right side perspective view thereof; and,

FIG. 10 is an enlarged rear, bottom and left side perspective view thereof.

The broken line showing in FIGS. 1 through 8 are for illustrative purposes only and forms no part of the claimed design.
